UNITED STATES PATENT OFFICE.

MICHAEL ZINSTEIN, OF NEW YORK, N. Y., ASSIGNOR TO THE SOVEREIGN SILK CO.,
OF NEW YORK, N. Y.

DESIGN FOR A SHOE.

Application filed July 21, 1923. Serial No. 6,819. Term of patent 3½ years.

To all whom it may concern:

Be it known that I, MICHAEL ZINSTEIN, a citizen of the United States of America, residing in the borough of Manhattan, city, county, and State of New York, have invented a new, original, and ornamental Design for Shoes, of which the following is a specification, reference being had to the accompanying drawing, forming a part thereof,

The drawing shows a perspective view of my new design embodied in a shoe of conventional shape.

I claim:—

The ornamental design for a shoe substantially as shown.

MICHAEL ZINSTEIN.
